(57) **CLAIM**

The ornamental design for a barbecue table, as shown and described.

DESCRIPTION

FIG. 1 is a front perspective view of a barbecue table, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is its state diagram;

FIG. 10 is an enlarged detail view of area 10 in FIG. 1; and, FIG. 11 is an enlarged detail view of area 11 in FIG. 2.

The broken lines in the drawings illustrate the portions of the barbecue table, which form no part of the claimed design. The dash-dot-dot broken lines encircling the enlarged views are for annotative purposes only and form no part of the claim thereof.

1 Claim, 11 Drawing Sheets
